UNITED STATES PATENT OFFICE.

ARTHUR P. HAASE, OF CHICAGO, ILLINOIS, ASSIGNOR TO OZONE PURE AIRIFIER COMPANY, A CORPORATION OF ILLINOIS.

OZONE MACHINE.

1,403,025.

Specification of Letters Patent. Patented Jan. 10, 1922.

Application filed April 14, 1921. Serial No. 461,386.

To all whom it may concern:

Be it known that I, ARTHUR P. HAASE, a citizen of the United States, and resident of Chicago, county of Cook, and State of Illinois, have invented certain new and useful Improvements in Ozone Machines, of which the following is a specification, and which are illustrated in the accompanying drawings, forming a part thereof.

10 The invention relates to ozone machine elements which may be used singly or in groups as is customary in devices of this class. The objects of the invention are to secure a high degree of efficiency, simplicity 15 of construction and ease of assembling and disassembling the parts.

A preferred embodiment of the invention is shown in the accompanying drawings, in which—

20 Fig. 1 is a side elevation, partly in section, of the improved element;

Fig. 2 is an end elevation, the open position of one of the clamping devices being shown in dotted lines;

25 Fig. 3 is a detail longitudinal sectional view, and

Fig. 4 is a transverse section on the line 4—4 of Fig. 1.

The improved element comprises a dielectric 10 preferably of glass taking the form of a cylinder which may be closed at one end, as 11, for the purpose of preventing the circulation of dust laden air through it. The outer electrode 12 is formed of two 15 sheets of metal 13, 14, each bearing a large number of contact points, as 15, shown as being stamped from the metal sheet. The metal sheets 13, 14, are bent to semi-cylindrical form, the width of each being such 20 that when the two are applied to the dielectric with the contact points 15 bearing thereagainst, they form substantially a complete cylinder.

The other electrode 16, is preferably 25 formed of a metallic foil and applied to the inner surface of the dielectric and is held in contact therewith by expansive spring elements, one of which, 17, is shown as an expansive metal band and the other, 18, is a 30 helical coil of spring wire which preferably forms a part of one of the circuit wires 19.

The parts which have been described being assembled are seated in a pair of chairs 20, 21, each having feet 22, 23, which may 35 be secured to a suitable support by means of

screws. A curved clamping bar 24 is pivoted, as shown at 25, to one of the side arms of each of the chairs and may be closed down over the electrode 12. The free end of the bar 24 is provided with a hook 26 for engagement by a latch 27 carried by a hasp 28 pivotally attached, at 29, to the other arm of the chair.

The contacts 15 are of uniform length so that all of them rest upon the dielectric 65 when the parts are assembled. One of the circuit wires 30 may conveniently be connected with the electrode 12 through one of the chairs, as 20, and is shown as secured thereto by one of the securing screws 31. 70

In use a high potential current being passed through the circuit, an arc is developed between each of the contacts 15 and the electrode 16 causing the generation of ozone in a well known manner. 75

In devices of this general character, there being a circulation of air among the contact points 15, dust is accumulated which must be removed. By disengaging the latch members 27 and throwing back the clamping bars 80 24, the two parts of the electrode 12 and the dielectric may be literally separated for the purpose of cleaning.

I claim as my invention:

1. In an ozone machine, in combination, 85 a cylindrical dielectric, an electrode in contact with the inner surface of the dielectric, an electrode inclosing the dielectric and formed of two separable semi-cylindrical plates, and readily releasable clamping elements for binding the last named electrode to the dielectric.

2. In an ozone machine, in combination, a cylindrical dielectric, an electrode in sheet form for bearing against the inner face of 95 the dielectric, expansible spring elements for holding such electrode against the dielectric and an electrode engaging the outer face of the dielectric.

3. In an ozone machine, in combination, a 100 cylindrical dielectric, an electrode in sheet form spring-pressed against the inner surface of the dielectric and an electrode engaging the outer surface of the dielectric.

4. In an ozone machine, in combination, a 105 cylindrical dielectric, and a pair of electrodes engaging the inner and outer surfaces of the dielectric, the inner electrode being a metallic sheet, and an expansible helical coil bearing outwardly against such sheet. 110

5. In an ozone machine, in combination, a cylindrical dielectric, an electrode comprising a pair of curved metal sheets inclosing the dielectric, a chair in which one of 5 curved sheets is seated, and a releasable clamping element for binding the two parts of the electrode to the chair.
6. An ozone machine element comprising a separable dielectric and electrode, a chair 10 for the element, and releasable clamping means for binding the element to the chair and holding the named element members in engagement.
7. An ozone machine comprising a cylindrical dielectric, an electrode in sheet form 15 engaging the inner surface thereof, and a leading-in wire having its end portion formed into an expansible helical and applied to the electrode to bind it against the 20 dielectric.
8. In an ozone machine, in combination, a cylindrical dielectric, and a pair of electrodes engaging the inner and outer surfaces of the dielectric, the inner electrode being a 25 metallic sheet, an expansible element bearing outwardly against the sheet, and a leading-in wire connected with such element.
9. In an ozone machine, in combination, a cylindrical dielectric, an electrode contigu- ous to the inner surface of the dielectric, a 30 removable electrode contiguous to the outer surface of the dielectric, and readily releasable clamping means for holding the outer electrode in operative position.
10. In an ozone machine, in combination, 35 a dielectric, a pair of electrodes respectively contiguous to the opposite faces of the dielectric, and readily releasable clamping means for holding the electrodes in operative position. 40
11. In an ozone machine, in combination, a dielectric, a pair of electrodes respectively contiguous to the opposite faces of the dielectric, and readily releasable clamping means for holding one of the electrodes in 45 operative position.
12. An ozone machine comprising, in combination, a separable dielectric and electrode, and readily releasable means for securing such two elements in contact. 50
13. In an ozone machine, in combination, a dielectric, a pair of electrodes respectively contiguous to the opposite faces of the dielectric, and readily releasable clamping means for holding each of the electrodes in 55 operative position.

ARTHUR P. HAASE.
